(57) **CLAIM**

The ornamental design for a faucet, as shown and described.

DESCRIPTION

FIG. 1 is a perspective view of a faucet, showing my new design;

FIG. 2 is another perspective view thereof;

FIG. 3 is a perspective view in the using configuration thereof;

FIG. 4 is a front view thereof;

FIG. 5 is a rear view thereof;

FIG. 6 is a left side view thereof;

FIG. 7 is a right side view thereof;

FIG. 8 is a top plan view thereof; and

FIG. 9 is a bottom plan view thereof.

FIG. 10 is an enlarged view of portion of FIG. 2 thereof; and, FIG. 11 is an enlarged view of portion of FIG. 2 thereof. The broken lines shown in the drawings illustrate portions of the faucet that form no part of the claimed design.
